US0D1017574S

(12) **United States Design Patent** (10) **Patent No.:** **US D1,017,574 S**
(45) **Date of Patent:** **** Mar. 12, 2024**

(54) **HEADPHONES**

(71) Applicant: **AUSTRIAN AUDIO GMBH**, Vienna
(AT)

(72) Inventor: **Patrice Billaudet**, Markt Piesting (AT)

(73) Assignee: **AUSTRIAN AUDIO GMBH**, Vienna
(AT)

(**) Term: **15 Years**

(21) Appl. No.: **29/876,592**

(22) Filed: **May 24, 2023**

Related U.S. Application Data

(62) Division of application No. 29/790,250, filed on Nov. 15, 2021, now Pat. No. Des. 999,756.

(30) **Foreign Application Priority Data**

(57) **CLAIM**

The ornamental design for headphones, as shown and described.

DESCRIPTION

FIG. 1 is an upper, front, and left side view of headphones showing the new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a lower, rear, and right side view thereof.

Features shown in broken lines form no part of the claimed design.

1 Claim, 7 Drawing Sheets
